Primary Examiner — Jennifer L Rempfer*Assistant Examiner* — Rene H. Kadoo(57) **CLAIM**

The ornamental design for a chainsaw holder, as shown and described.

DESCRIPTION

FIG. 1 is a top plan view of the chainsaw holder;
FIG. 2 is a front elevation view of the chainsaw holder thereof;

FIG. 3 is a bottom plan view of the chainsaw holder thereof;
FIG. 4 is a left elevation view of the chainsaw holder thereof;

FIG. 5 is a right elevation view of the chainsaw holder thereof;

FIG. 6 is a front top isometric view of the chainsaw holder thereof; and,

FIG. 7 is a front top isometric view of the chainsaw holder showing a chainsaw inserted as used.

The dotted lines in FIG. 7 represent the environment and form no part of the claimed design.
